UNITED STATES PATENT OFFICE

STANLEY B. FREIBERG, OF CINCINNATI, OHIO

TRAY GUIDE FOR FILING CABINETS

Original application filed December 12, 1928, Serial No. 325,589. Divided and this application filed March 17, 1930. Serial No. 436,367.

This is a divisional application of application Serial Number 325,589, filed December 12, 1928.

The present invention relates to a tray mounting or guide for use in cabinets and the like, particularly, filing cabinets.

An object of the invention is to provide such a guide which is an independent member removable from a cabinet with which it is used.

Another object is to provide such a device having a new form of cooperation with the cabinet and tray with which it is used.

Another object is to provide a guide simple and substantial in structure and efficient in operation.

These objects are attained by the means described herein and set forth in the accompanying drawing, in which:

Fig. 1 is a perspective view of a guide or mounting of the present invention.

Fig. 2 is a partial side elevational view of a cabinet having a guide of the present invention mounted therein and supporting a filing tray.

Fig. 3 is a top plan view of the rear portion of a tray suitable for use with the guide of this invention.

Fig. 4 is a view taken on line 4—4 of Fig. 1.

The guide 10 is U-shaped and has channelled arms 11 and back 12 rigidly secured together, the apertured sides of the arms and back facing inwardly of the guide. Arms 11 at their rear ends may be formed with extensions 13 within which the end portions of the back 12 may be secured, as by welding.

A pair of oppositely-disposed lugs 14 is provided, one each, on the arms 11 adjacent the front ends thereof and extending outwardly of the guide. Lugs 14 may be suitably formed by striking outwardly small portions of the sides of arms 11. The front ends of arms 11 are formed so as to provide the narrowed vertical walls 15 and the end abutments 16. Aligned apertures or ways 17 communicating with the channels of arms 11, are provided adjacent the ends of arms 11. A suitable bumper 18 extends inwardly from the back 12 of guide 10.

Guide 10 is adapted to fit snugly between

two of the shelves 19 and between the sides 20 of a suitable cabinet 21. The length of arms 11 of guide 10 is less than the cabinet's length. Guide 10 is somewhat resilient so that the arms 11 thereof may be pressed toward one another for permitting passage of lugs 14 beyond front inner edge abutments 22 provided on cabinet 21 by turning inwardly the front edge portions of the cabinet. After lugs 14 have passed abutments 22, the arms 11 spring back to their normal positions and abutments 22 prevent withdrawal of guide 10 from the cabinet until pressure is again applied to arms 11.

Guide 10 is adapted to cooperate with a tray or drawer 23, such as that set forth and claimed in co-pending application, Serial Number 325,589, which has pivot studs or rods 24 extending outwardly of the tray sides at the extreme rear of the tray. When guide 10 has been positioned in its cabinet, as shown in Fig. 2, the tray can be operatively positioned by inserting the pivot studs 24 through the aligned ways 17 into the channels provided by arms 11. In this position, the tray may be allowed to hang down vertically from the cabinet, suspended from guide 10, the pivot studs 24 being in contact against the end abutments 16. By reference to Fig. 2 it will be seen that lugs 14 are so spaced from the front ends of arms 11 that said ends are permitted, in the operative position of the guide, to project outwardly of the cabinet to a slight extent. Fig. 2 shows the normal, operative position of the tray, the convenient method of thus supporting the tray being to pull out one of the trays immediately beneath.

When tray 23 is pushed into the cabinet, the studs 24 move backwardly within their respective channels until the back of the tray contacts the bumper 18 whereupon the backwardly-moving tray carries guide 10 with it to the rear of the cabinet so that the projecting front ends of the guide are enclosed within the cabinet.

What is claimed is:

1. In combination, a cabinet having inner abutments adjacent the front, spaced supports in the cabinet, U-shaped guide mem-

bers slideable one each on said supports and having lugs thereon for contacting the abutments for preventing normal movement of the guide members past said abutments, and trays each slideably and releasably supported by one of the guide members and pivotally suspended thereby exteriorly of the cabinet when withdrawn from their positions in the cabinet the arms of each U-shaped guide member being movable toward one another in a common plane to permit removal of the guide by movement of said lugs past said cabinet abutments.

2. As a new article of manufacture, a tray guide comprising two arms joined by a rigid cross-member, said arms being resiliently movable in a common plane and being provided with a pair of oppositely disposed apertures and opposed channels communicating therewith and extending longitudinally of the arms, abutments closing the channels at one end of the guide, and lugs extending outwardly from the side members.

3. The combination with a tray having laterally-extending studs at its rear and a cabinet having tray-supporting means therein and inwardly-projecting abutments at its front, of a U-shaped tray guide slideable upon said supporting means and having channeled arms closed at their free ends and one of said arms being provided adjacent its end with a recess for permitting insertion of said studs into said channeled arms, and lugs extending laterally of said arms adjacent the free ends thereof and adapted to contact said inwardly-projecting abutments for normally limiting movement of the guide outwardly of the cabinet, the tray being pivotable upon said studs within the closed free ends of the arms in the outwardly-projecting position of the guide, and the arms, upon removal of the tray therefrom, being movable toward one another in a common plane to permit movement of said lugs past said abutments whereby to remove the guide from the cabinet.

4. The combination with a cabinet having inwardly-projecting abutments at its front, of a filing tray having a laterally-extending stud at each side of its rear, and a U-shaped guide adapted for slideable insertion in the cabinet and having channeled arms for slideably receiving said studs, means closing the free ends of the arms and adapted to cooperate with said studs for permitting pivotal movement of the tray upon said ends, and lugs extending laterally of the arms and adapted normally to limit outward movement of the guide by contact of the lugs with said inwardly-projecting cabinet abutments, said arms, with the tray removed therefrom, being resiliently movable toward one another in a common plane to permit removal of the guide.

5. The combination with a filing cabinet,

of a tray, a U-shaped guide slideable in the cabinet and having resilient arms adapted to slidably support the tray, means normally limiting slideable movement and projection of the guide relative to the cabinet, and means for pivotal movement of the tray upon the guide in the projecting position of the guide, said resilient arms, upon removal of the tray therefrom, being movable toward one another in a common plane for rendering inoperative said movement-limiting means, whereby the guide may be withdrawn from the cabinet.

6. In combination with a cabinet and a tray, a U-shaped guide adapted to support the tray relative to the cabinet and having channeled sides opening inwardly of the guide, abutments on the guide for closing the channels at the free end of the guide, the sides of the guide providing oppositely disposed apertures communicating with the channels, and oppositely disposed lugs extending outwardly from the sides adjacent the free ends thereof.

7. As a new article of manufacture, a tray guide comprising two side members joined by a cross member, said sides providing a pair of oppositely disposed apertures and opposed channels communicating therewith and extending longitudinally of the sides, abutments closing the channels at one end of the guide, and lugs extending outwardly from the side members.

8. As a new article of manufacture, a tray guide comprising two side members and a single cross member, the side members providing a pair of oppositely disposed apertures with opposed channels communicating therewith and extending longitudinally of the guide, the cross member being so secured to the side members that movement of one side member of the guide causes a corresponding movement of the guide as a whole.

9. The combination of a filing tray having a transverse rod projecting on each side adjacent its rear and a unitary U-shaped guide having parallel side members channeled longitudinally thereof, the guide being adapted for horizontal slideable insertion within a cabinet, the free ends of the guide being closed and one of said ends being provided in its top portion with an aperture by which to admit the ends of the above transverse rod into the channels provided by the guide, and with lugs by which to prevent withdrawal of the guide from the cabinet after the ends of the rod have been thus inserted.

10. In combination, a cabinet having inner abutments adjacent the front, spaced supports in the cabinet, unitary U-shape guide members slideable on said supports, said guide members comprising arms having lugs thereon for preventing normal movement of the guide members past said abutments, the arms being relatively movable whereby to deflect

the arms to permit movement of the lugs past the abutments, and trays slidably held by the guide members and removably suspended thereby exteriorly of the cabinet when withdrawn from their positions in the cabinet, the 5 trays when received by the guide members precluding deflection of the arms and assuring contact of the lugs on the guide and the abutments of the cabinet whereby to preclude accidental separation of the tray, cabinet and 10 guide.

In testimony whereof, I have hereunto subscribed my name this 15th day of March, 1980.

STANLEY B. FREIBERG.
